METHOD OF AND MEANS FOR ROLLING
CHANNEL OR LIKE SECTIONS FROM
STRIP METAL

Charles Victor Smith, Weybridge, Surrey, England, assignor, by mesne assignments, to Vickers-Armstrongs Limited, London, England

Application June 27, 1938, Serial No. 216,106
In Great Britain October 5, 1937

9 Claims. (Cl. 153—3)

This invention relates to the method of and means for manufacturing channel, angle or other like rolled sections (hereinafter termed channel sections) from a strip by passing the strip through a series of rolls which progressively bend or fold the strip to a channel form. In using such a section in structures, and particularly aircraft structures, it is necessary to shape the section to a certain predetermined profile, the curve of which profile may or may not be circular but may be elliptical, parabolic or other non-circular form and moreover may vary at different parts of the section.

According to this invention, in the rolling of channel sections from a flat strip by a series of rolls which progressively bend or fold the strip to its channel form, the step is introduced of simultaneously moving some of the rolls across the direction of travel of the strip to curve the axis of the channel to a predetermined profile during the action of rolling.

The rolls may, during the travel of the strip, be moved to and maintained at a constant position relatively to each other to bend the channel to a curve of simple or circular form or they may be moved progressively with the travel of the strip to bend the channel to a curve of complex or variable form, i. e., an ellipse or parabola or a combination of these.

Apparatus for rolling such channel sections comprises a series of rolls for progressively bending or folding the strip to a channel form, devices for carrying said rolls, some of which devices are arranged to slide transversely of the direction of travel of the strip and to tilt to keep the rolls normal to the strip in all positions and means for displacing said devices during the movement of the strip through the rolls. Thus, the pairs of rollers so displaced are caused to take up their correct positions at any instant on the predetermined profile of the axis of the channel, whether the profile is one of constant curvature or of variable curvature.

The displacement of the devices carrying the pairs of rolls is effected by single or multiple cams and in the case of multiple cams each of these comprises multiple cam elements with follower elements, one of which elements, for instance the follower element, is adjustable and can be set in any one of a number of different positions depending upon the desired profile of the axis of the channel being rolled. Thus without the changing of cams or any other alteration except the setting of the follower elements, the apparatus can be used for the cold rolling

of channel sections of a large number of different profiles, whether semicircles, ellipses, parabolas or similar curves, or a combination of such curves.

Diagrams indicating one means for manufacturing channel sections by the method according to this invention are shown by way of example in the accompanying drawings, in which:

Fig. 1 is a sectional plan with the roll housings in one position.

Fig. 2 is a similar view to Fig. 1 but showing the roll housings in another position.

Fig. 3 is a side elevation of one of the cams and its follower.

Figs. 4 to 9 are sections on the lines IV—IV, V—V, VI—VI, VII—VII, VIII—VIII and IX—IX respectively in Fig. 2, showing the progressive stages of bending of the strip in producing a typical channel section according to this invention.

In a practical embodiment, the strip A to be folded to channel form and bent to a predetermined curvature is supplied from a reel 1 and passes through say six roll housings marked 2, 3, 4, 5, 6 and 7, each containing at least one pair of rolls, which progressively fold the strip to the required form which may be as shown a channel with the web of the channel corrugated and with the ends of the flanges bent inwardly for stiffening purposes. The first three housings 2—4 are fixed but the last three roll housings 5 to 7 are so mounted that they can be slid transversely of the direction of travel of the strip and can also tilt angularly in proportion to the sliding adjustment, as shown in Fig. 2. For instance, they are mounted on pivots 8, 9 and 10, respectively, carried by slides 11, 12 and 13 by which they can be moved transversely and two housings 5 and 6 are provided with extensions 14, 15 pivoted on fixed pivots 16, 17 arranged that when moved transversely they swing about an arcuate path so that they are thereby tilted into the required positions. The third housing 7 is similarly arranged but as the swinging movement is larger than that of the other two, instead of being pivoted it is provided with an extension 18 carrying a roller 19 working in a cam guide 20.

The positioning and tilting of these roll housings is carried out by a series of three cams 21, 22, 23, mounted on three vertical spindles 24, 25 and 26 at the rear of the machine. Each cam comprises a series of cam elements 27 to 42 of approximately sector shape arranged in staggered relationship as shown. The multiple cam

elements on each spindle are arranged in the form of a spiral and engage with a slotted follower element 43 carrying a series of follower rollers 44 mounted on carriers 45 which are 5 slideable in the slots 46 in the follower and are thus adjustable in relationship to each other and to the cam elements, so that by adjusting and fixing the follower rollers with their carriers at any desired position, the cam elements will im- 10 part to the slidable roll housings the necessary amount of transverse movement according to the predetermined profile to be given to the channel section. The position of the rollers 44 on each follower is conveniently determined by distance 15 pieces 47 which fit in the slots 46 between the roller carriers 45 and the closed ends of the said slots in the follower. Clamping devices 60 are provided for securing the follower elements in their adjusted position. The cam and fol- 20 lower elements are so set that a balanced thrust is imparted to the follower 43. Each slotted fol- lower is connected to the slides 11, 12 and 13 through rods 48 and each follower is held in contact with the cam elements during the return 25 stroke by a spring or springs, such as 49 or by a pneumatic piston (not shown). Where a pneu- 30 matic piston is employed the air for operating the pneumatic piston may be controlled by a valve adapted to admit compressed air at defi- nite intervals.

The driving of the rolls in the three housings 5, 6 and 7 must be effected in such a manner that it is not interrupted by the transverse and tilting movements and this may, for example, 35 be secured by connecting each roll in said housings with a short spindle 50 having Hook's joints 51 at each end by which the roll is connected to a counter-shaft 52 free to slide in a gear box 53, said counter-shaft having a short pinion 54 in 40 constant mesh with a long pinion 55 rotatably mounted in said box and in driving engagement through the gearing 56 with a shaft 57. Thus the counter-shaft is permitted to slide trans- versely with the rolls as these move transversely 45 while the spindles 50 permit the rolls to tilt with the housings, without interfering with the drive.

The cams 21, 22, 23 are driven by gearing 58 and a shaft 59, which is interconnected in a suitable way (not shown) with the shaft 57 driving 50 the forming rolls so that the cams and rolls are driven synchronously.

Figs. 4 to 9 show typical sections of strip material bent by the apparatus hereinbefore described and illustrated. The strip being fed in 55 at one end of the machine and being first flattened and then progressively bent to the desired final form, which in the example illustrated is a channel with inturned flanges and a corrugated or dished web, and also bent to the desired profile 60 curve. By displacing the housings 5, 6 and 7 to, and maintaining them at a constant position, the curve to which the channel so formed will be bent will be of a simple form but by varying the positions of the said housings by the cam 65 and follower mechanisms, as the strip continues to be fed through the rolls, the channel section can be bent to a complex curve of any form within limits. In operation the strip is first fed 70 through the rolls while these are in the position shown in Fig. 1 until the strip extends from the housing 2 to the housing 7 and is in engagement with the rolls in each housing and then the housings 5, 6 and 7 are displaced to impart the necessary curvature to the strip, while the feeding of the 75 strip is continued until a predetermined length of

channel folded and bent is formed. This length is then cut off from the remainder of the strip. The formation of this length constitutes a cycle of the machine operation and this cycle may be repeated indefinitely, a geared pointer and dial 5 (not shown) driven from the shaft 57 may be provided conveniently to indicate the beginning and end of each cycle.

One of the important advantages of this machine is the considerable saving in material which 10 arises from the pre-forming and bending of the material in strip form, permitting the exact length to be cut off. Other advantages will be apparent from the foregoing description.

What I claim as my invention and desire to 15 secure by Letters Patent is:

1. The herein described method of producing curved rolled sections from flat strip material which consists in feeding the strip through a series of rolls adapted to roll the strip progressively to the required section, and simultaneously moving at least some of the rolls transversely across the direction of travel of the strip and angularly to maintain the rolls approximately at right angles to an axis of the strip in all positions. 20

2. The herein described method of producing curved rolled sections from flat strip material which consists in feeding the strip successively through a series of aligned rolls adapted to act 30 on the strip and progressively bend it to the required section as it passes through the rolls from one end to the other, and simultaneously moving some of the last rolls through which the strip passes across the direction of travel of the strip 35 and angularly to keep the displaced rolls approximately at right angles to the strip in all positions.

3. Apparatus for producing curved rolled sections from strip material comprising a series of 40 rolls for progressively rolling the strip to a required sectional form, means for carrying at least some of the said rolls so that they can be moved transversely of the strip and also tilted to keep the rolls approximately normal to the strip 45 at all positions and means for displacing said carrying means during the movement of the strip through the rolls.

4. Apparatus for producing curved rolled sections from strip material comprising a series of 50 rolls arranged to act successively on the strip to roll it to a required sectional form, means for mounting at least some of the said rolls so that they can be moved relatively to the others in a direction transversely of the movement of the 55 strip and so that they can also be tilted to keep the rolls approximately normal to the strip at all positions and means for displacing said mounting means during the movement of the strip through the rolls. 60

5. Apparatus for producing curved rolled sections from strip material comprising a series of aligned rolls arranged to act successively on the strip to roll it to a required sectional form, means for mounting at least some of the said rolls so 65 that they can be moved out of their aligned position in a direction transversely of the movement of the strip and so that they can also be tilted to keep the rolls approximately normal to the strip at all positions and means displacing 70 said mounting means while the strip is being fed through, and acted on by, the rolls.

6. Apparatus for producing curved rolled sections from strip material comprising a series of rolls arranged to act in succession on the strip 75

and roll it to a required sectional form, means for carrying some of the said rolls so that they can be moved transversely of the movement of the strip and also tilted to keep the rolls approximately normal to the strip at all positions and cam mechanism for displacing said carrying means during the movement of the strip through the rolls.

7. Apparatus for producing curved rolled sections from strip material comprising a series of rolls arranged to act in succession on the strip and to roll it to a required sectional form, means for driving said rolls, means for carrying some of the said rolls so that they can be moved transversely of the movement of the strip and also tilted to keep the rolls approximately normal to the strip at all positions, means for connecting said movable rolls with said driving means in such a manner that they can be displaced without interrupting the drive, cam mechanism displacing said carrying means during the movement of the strip through the rolls and means for driving said cam mechanism synchronously with said means for driving the rolls.

8. Apparatus for producing curved rolled sections from strip material comprising a series of aligned rolls for successively acting on the strip and rolling it to a required sectional form, means for carrying at least some of the said rolls so that they can be moved transversely of the movement of the strip and also tilted to keep the rolls approximately normal to the strip at all positions and multiple sector-shaped elements

arranged in staggered positions on a spindle and arranged in the form of a spiral and follower elements attached to said carrying means for the rolls adapted to be engaged by said sector-shaped elements, one of which elements is adjustable and can be set in any one of a number of different positions depending upon the desired curvature of the axis of the section being rolled, whereby the said cam and follower elements displace said carrying means during the movement of the strip through the rolls.

9. Apparatus for producing curved rolled sections from strip material comprising a series of rolls arranged successively to act on the strip and roll it to a required sectional form, means for carrying at least some of the said rolls so that they can be moved transversely of the movement of the strip and also tilted to keep the rolls approximately normal to the strip at all positions, and cam mechanism for displacing each of said movable carrying means during the movement of the strip through the rolls, said cam mechanism comprising multiple sector-shaped elements arranged in staggered positions on a spindle and arranged in the form of a spiral, follower elements adapted to engage with said sector-shaped elements, said follower elements being adjustable on a follower connected to the said roll carrying means, distance pieces for determining the position of said follower elements relative to the follower and means for setting the follower elements in any adjusted position on the follower.

CHARLES VICTOR SMITH.
